MEANS FOR APPLYING ARTIFICIAL RESPIRATION

Vivian Ray Bennett, Los Angeles, Calif.

Application February 1, 1950, Serial No. 141,748

11 Claims. (Cl. 128—30)

1

This invention relates to kinesitherapy, and more particularly to the science of life extensions by artificial respiration.

In the treatment for the control of poliomyelitis it is common practice to place the patient within a respirator whereby his chest is subjected alternately and at regularly repeated intervals to negative and positive pressure, to expand and contract the thoracic cage and thereby artificially induce the regular inhalation and exhalation steps of breathing which his paralyzed condition makes it impossible for him to continue naturally. Whereas the requirements for different patients and, in fact, for each individual patient as his condition varies, are subject to a comparatively wide range of variation, in the usual case it is necessary to operate the conventional respirator so that the pressure therein alternates at regular intervals from minus 12 to 18 centimeters of water pressure to plus 2 to 3 centimeters of water, i. e., a pressure variation of approximately 15 to 20 centimeters of water pressure. But in cases of unusually severe paralysis, or of especially severe or extensive congestion of the lungs, it becomes necessary, in order to attain adequate ventilation of the lungs, to operate the respirator over a wider range of pressure variation by increasing the degree of negative pressure in order to cause a sufficient volume of respiration. Unfortunately, such treatment often proves inadvisable, or even dangerously severe in a large number of cases, as the excessively high degree of negative pressure necessary, often as high as 25 to 27 cm. of water pressure, is apt to cause complications. The exact mechanism is not fully understood, but patients often will develop mucus, pulmonary edema, atelectasis or other conditions very detrimental to respiration.

One of the problems, therefore, for which a solution is provided in the present invention is that of assuring adequate ventilation of the lungs of an iron-lung patient, without resorting to an excessive degree of negative pressure. It should be pointed out also that a high negative pressure is usually difficult to maintain because of leaks around the collar seal and other parts.

A more detailed object in this connection is to supplement the normal respiratory action of a standard respirator by supplying synchronized intermittent positive pressure internally, so as to inflate the patient's lungs.

In still further detail, the present invention seeks to supply the gas or gases to be inhaled at a pressure adequate to overcome the resistance of

2

the upper respiratory tract, the tracheotomy tube, if one is being used, and aid in expanding the lung by internal pressure inflation.

Another object of my invention is to provide apparatus of a simple, durable, and thoroughly dependable nature by which improved methods of treatment can be carried out, and which is capable of being mounted upon and operably coupled to a standard respirator, for operation synchronously therewith, so simply and easily that interruption of the respirator's normal functioning is unnecessary.

A further object is to provide apparatus of the general character indicated for providing intermittent positive pressure breathing in proper synchronism with a standard respirator, which permits the patient to exhale naturally into the atmosphere after each inspiration with virtually no pressure or flow resistance, and without any material waste of the gases being administered, and with a minimum amount of re-breathing.

A still further object is to make provision for ready adjustment of the accessory apparatus of the present invention, so that the pressure at which gas is administered can be regulated almost instantly, and thus insure against almost any clinical emergency, and to enable the accessory attachment to take over the entire responsibility of inducing breathing of a paralyzed patient as during respirator pressure failure emergencies, or to permit opening of the respirator for such functions as nursing care, medical treatment, transfer of the patient to another respirator, or even surgery.

The invention possesses other objects and features of advantage, some of which, with the foregoing, will be set forth in the following description of the preferred form of my invention which is illustrated in the drawings accompanying the forming part of the specification. It is to be understood that I do not limit myself to the showing made by the said drawings and description, as I may adopt variations of the preferred form within the scope of my invention as set forth in the claims.

Referring to the drawings:

Figure 1 is a perspective view of a standard respirator having a respirator pressure attachment incorporating the principles of the present invention operatively installed thereupon for use in operating co-operatively therewith in performing my improved method of administering artificial respiration which also constitutes a portion of the present invention.

Figure 2 is an enlarged perspective view of the gas pressurizing assembly portion of the respirator attachment of the present invention, showing the manner of its being mounted upon and of being synchronized into the cycle of the respirator. Portions of the figure are broken away and shown in section to reduce the size of the figure and the better to illustrate parts of the apparatus.

Figure 3 is an end elevation of the respirator and respirator attachment of Figure 1, drawn to a slightly reduced scale, with parts broken away the better to reveal constructional detail.

Figure 4 is an enlarged detail view in vertical section taken upon the line 4—4 of Figure 3, to illustrate the clamp whereby the movable element of the auxiliary bellows is coupled to the oscillating lever of the respirator's bellows' operating mechanism.

Figure 5 is an enlarged detail view of the auxiliary bellows and associated portions of the gas pressurizing assembly of the respirator attachment.

Figure 6 is a longitudinal vertical sectional view of the pressure control box assembly portion of the respirator attachment.

Figure 7 is an enlarged detail view in horizontal section taken on the line 1—1 of Figure 6, with the direction of view as indicated.

Figure 8 is a view in side elevation of the head assembly portion of the respirator attachment.

Figure 9 is an enlarged detail view in vertical section taken medially through a portion of the head assembly of Figure 8.

Figure 10 is a diagram illustrating schematically the several portions of the positive pressure respirator attachment of the present invention, showing the manner of their association with each other and with the bellows of the respirator proper.

Figure 1 illustrates the manner in which the positive pressure respirator attachment of the present invention is mounted upon a standard respirator of conventional design. Whereas the conventional respirator chosen for illustration in conjunction with my positive pressure attachment is of the tank type adapted to receive the entire body of a patient with the exception of his head, commonly known in the trade as the Drinker-Collins respirator, or "iron lung," it should be understood that my respirator attachment is adaptable with equal facility and equal efficiency of operation upon respirators of other types.

The respirator chosen for illustration comprises a relatively large shell 11 adapted to be hermetically sealed so that a differential in pressure between the interior and the exterior of the shell 11 can be established. The shell is large enough to receive the entire body of a patient with the exception of his head 12 which protrudes through one end 13 of the shell 11 to which the end 13 is preferably detachably secured, as by a plurality of clamps 14. Conventionally, a relatively large bellows 16 is mounted below the shell 11, the upper end or head 17 of the bellows 16 being rigidly secured to the under side of the shell 11 through which communication between the interior of the bellows 16 and the interior of the shell 11 is established by a suitable port or passageway (not shown). The lower or movable head 18 of the bellows 16 is supported by a pitman arm 19 to which it is preferably rigidly connected and which extends rigidly upward from a substantially horizontal lever 21, one end of which is

pivoted as by a pin 22 to one of the legs 23 of the frame 24 upon which the shell 11 of the respirator is mounted. A driving motor 26 is supported upon a platform 27 also carried by the frame 24 and this motor is operably connected as by a belt 28 to a set of speed reduction gears (not shown) operable within a suitable gearbox 29 through one wall of which the driven shaft 31 extends to receive a crank 32 operably engaged with the lower end of a connecting rod 33. The upper end of the connecting rod 33 is pivotally connected to a crosshead 34 adjustably mounted upon the lever 21 beyond the pitman arm 19 thereon from the pivot pin 22. By sliding the crosshead 34 along the lever 21 toward or away from the pivot pin 22, the distance through which the lever 21 is reciprocated each time the crank 32 makes a complete revolution is increased or decreased respectively as is also the length of stroke of the lower head 18 of the bellows 16. It is apparent, therefore, that adjustment of the crosshead 34 attains variation of the quantity of air that it forces into the shell 11 and, during the next phase of its cycle of operation, that it withdraws from the shell 11. It is likewise apparent that energization of the motor 26 results in attaining fluctuation of the air pressure within the shell 11 from a negative pressure caused by withdrawal of air from the shell 11 as the bellows 16 expands as the result of downward movement of its lower head 18; and that similarly positive pressure is attained within the shell 11 as the result of collapsing of the bellows 16 coincident with the upward movement of the movable head 18. The magnitude of both these positive and negative pressures is determined by the positioning of the crosshead 34 upon the lever 21, a locking screw preferably operated by a hand grip 36 being provided upon the screw to facilitate 40 clamping the cross head 34 in selected position of adjustment upon the lever 21.

It is customary medical practice to treat for the control of poliomyelitis by placing a patient with his entire body except his head 12 within such a shell 11 and, after sealing the opening in the head end 13 thereof through which the patient's head extends as by a flexible, impervious collar 42, to induce artificial respiration in the patient by operation of the bellows 16 in accordance with the hereinabove description. When the bellows 16 is expanded, the consequent negative pressure created within the shell 11 will cause the patient's thoracic cage to expand in much the same manner as in natural breathing but without requiring any muscular activity on the patient's part, thus compensating for the inability of the paralyzed muscles of his respiratory system to function normally. Such expansion of his thoracic cage develops a partial vacuum within the patient's lungs, with the result that a quantity of air will be drawn through the patient's respiratory tract into the lungs, thereby oxygenating the patient's lungs sufficiently to prevent asphyxiation in most cases. However, as indicated in the objects of the present invention, as hereinabove recited, in extreme cases it frequently develops that sufficient oxygen to maintain life cannot be drawn into the patient's lungs in this manner without resorting to such extreme negative pressure that the lung tissues are apt to be impaired, and it is for the purpose of overcoming this and other disadvantages of conventional "iron lung" practice that the apparatus of the present invention has been designed.

The positive pressure respirator attachment of the present invention comprises in general a gas-pressurizing unit indicated in its entirety at 51, a pressure control box assembly 52 and a head assembly 53 which includes a suitable supply tube 54 whereby it is connected to the pressurizing unit 51 and to the pressure control box assembly 52, as will be described in detail hereinbelow.

Referring first to Figures 1 to 5, inclusive, the pressurizing unit comprises an auxiliary bellows 56 having a lower stationary head 57 and an upper movable head 58 interconnected by a flexible, impervious, and preferably corrugated sleeve 59. The lower stationary head 57 of the bellows 56 is supported upon a tubular nipple 61 by means of which communication is established between the interior of the bellows 56 and the bore 62 of an air and gas inlet housing 63 upon which the nipple 61 also is supported. Extending laterally and preferably at a slight angle from the housing 63 is an arm 64 from the outer end of which preferably a pair of spaced dependent flanges 66 and 67 extend to embrace an upwardly extending flange 68 of a rigid, horizontal bar 69 of the framework 24 of the respirator. Clamping screws 71 carried by the flange 67, permit securing the inlet housing 63 rigidly but removably upon the frame bar 69, as clearly illustrated in Figure 2.

A bracket 72 is rigidly secured to the upper head 58 of the auxiliary bellows 56 as by a suitable fastening screw 73, and extends laterally therefrom so that a downwardly extending clamp 74 can be secured to the lever 21 of the respirator's bellows' actuating mechanism. As best shown in Figure 4, this clamp 74 comprises an arm 76 extending downwardly from the bracket 72 and having a flange 77 extending inward at its lower end. A strap 78 is carried by a screw 79 extending through both the strap 78 and the arm 76. This screw is provided with a nut 81 engaging the outer face of the arm and a head 82 engaging the outer face of the strap 78 so that when the screw 79 is tightened into its nut 81 the strap 78 is drawn forcefully toward the arm 76. The parts are so proportioned and arranged that the horizontally extending lever 21 of the respirator's actuating mechanism is receivable between the flange 77 and the proximal end of the strap 78, the opposed faces of which are preferably beveled, as indicated at 83 and 84 respectively, to enhance the security of their engagement upon the opposite edges of the lever 21 when the screw 79 is tightened. The head 82 of the screw 79 is provided with a convenient handle in the form of a transversely extending bar 86 permitting the tightening or loosening of the screw 79 manually and without requiring any tools.

An important consideration in this connection is that both the clamp 74 whereby the upper movable bellows' head 58 is operably mounted upon the lever 21 and the arm 64 and its flanges 66 and 67 are of such simple design and are arranged so that they can so readily be secured in proper position upon their respective associated portions of the respirator proper that the pressurizing assembly 51 can be mounted upon the respirator in operative position and connected thereto for operation in synchronism with the cyclic movements of the main bellows 16 very quickly and with such facility that it is not even necessary to shut down the respirator's operating mechanism. The importance of this detail lies in the fact that it is unnecessary to interrupt the operation of the respirator in order to mount my attachment thereupon for synchronized operation in conjunc-

tion therewith—a feature readily appreciated by anyone conversant with the circumstances under which poliomyelitis patients are treated in and with apparatus of this general type.

5 Mounted upon the inlet end of the housing 63 is an upwardly extending air inlet tube 91 upon the upper end of which is mounted a receptacle 92 adapted to receive a conventional filter pack 93. A check valve 94 below the filter pack 93 permits air to enter the housing 63 through the air inlet tube 91 but precludes escape of air through the air inlet tube 91. Means are also provided for the entry of oxygen or other suitable gas into the inlet housing 63 as by means of a manually operable valve 96, the bore of which is in communication with the bore 62 of the housing 63. To the outer end of the valve 96 a suitable tube 97 is affixed, this tube 97 being adapted to be connected to an oxygen tank 95 as indicated in Figure 1, or other suitable source of the gas or mixture of gases which the condition of the patient to be treated indicates.

Also in communication with the bore 62 of the housing 63 is an accumulator bag 98 preferably of conventional design and composed of suitable resilient impervious material. A check valve 99 is interposed between the portion 101 of the housing 63 into which the air inlet tube 91, the gas inlet valve 96, and the accumulator bag 98 open into the bore 62 and the portion 102 of the bore 62 with which the nipple 61 communicates. It might here be explained that the function of the accumulator bag 98 is to permit continuous flow of the gas to be administered to the patient through the valve 96 and into the portion 101 of the housing in spite of the fact that withdrawal of this gas from the portion 101 is intermittent since such withdrawal occurs only during an expansion or suction phase of the cycle of operation of the bellows 56. During a compression phase of the bellows 56 the check valve 99 prevents reversal of flow therewith and since the valve 99 then will be closed, the gas which continues to flow inwardly through the valve 96 will be stored within the accumulator bag 98 ready for withdrawing into the portion 102 of the housing 63 when the bellows 56 enters its next intake phase. Inasmuch as most patients do not require pure oxygen, but only a mixture of oxygen diluted with a predetermined proportion of air, the valve 96 will in most cases be so regulated that the total quantity of oxygen permitted to pass the valve 96 during the period of time required for a complete cycle of operation of the bellows 56 will be substantially less than the total volume of gas which the bellows 56 is adapted to receive and expel during each of its cycles. Consequently, when the bellows 56 first begins to expand it will draw the oxygen which theretofore has been stored within the accumulator bag 98, and, due to the slight and yet material resistance to such entry of air as is offered by the check valve 94, not until all of the oxygen so stored within the bag 98 has been withdrawn will air begin to enter the system through the filter pack 93.

As a precautionary measure, a safety valve 106 resiliently pressed into closing relationship as by a spring 107 is operatively associated with a port 108 in the lower, stationary head 57 of the bellows 56. The spring 107 is so designed that it will open in response to gas pressure within the bellows 56 at any time that the pressure of that gas exceeds the maximum internal pressure which safely can be permitted to be imposed upon the patient's respiratory system.

To the discharge end 111 of the housing 63 the supply tube 54 is connected preferably by means of a suitable coupling member 112. However, before passing through the coupling member 112 into the supply tube 54, gas must pass through another check valve 115 the function of which is to prevent reversal of flow of gas within the supply tube 54 during the expansion phase of the cycle of operation of the bellows 56.

Also leading from the discharge end 111 of the housing 63 is an auxiliary pressure tube 113, the bore of which is maintained in communication with the bore 62 through a by-pass 114 leading into the bore 62 between the two check valves 99 and 115, with the result that the pressure existing within the auxiliary tube 113 is equilibrated closely with that within the bore 62 of the housing 63 at any given time during the cycle of operation, without any resistance from the check valves.

Means are provided at the other end of the tube 54 for connecting it optionally to a facial breathing mask such as that indicated at 116 in Figure 1 or to a tracheotomy tube such as that indicated diagrammatically at 117 in Figure 10, depending upon the individual requirements of the patient being treated. In the modification illustrated, the connecting means comprises a tubular housing 121 best understood by reference to Figures 1, 8, and 9. This housing actually constitutes a continuation of the supply tube 54 inasmuch as it is securely and semi-permanently attached thereto as by having its inlet end 122 fitted tightly into the bore of the tube 54, thus placing the bore 123 of the housing 121 in communication with the bore of the outlet tube 54. Preferably, the housing 121 is of angular design comprising two branches 124 and 126. The branch 126 is provided with an exhaust or exhalation port 127 extending through a wall thereof parallel to the branch 124 so that a bracket 128 rigid with and extending laterally from the branch 124 extends past the outer end of the port 127. Accordingly, the bracket 128 is in convenient position to support a nipple 129 extending through the bracket 128, in coaxial alignment with the port 127. This nipple 129 is of tubular form and the auxiliary pressure tube 113 is connected to the end thereof opposite the port 127.

A hollow bulb 131 of resilient impervious material is mounted upon the face 132 of the bracket 128 which is proximal to the port 127, by having a peripheral edge 133 which defines the end of the neck 134 of the bulb 131 clamped between a head 136 on the nipple 129 and the bracket 128. The bore 137 of the nipple 129 opens into the interior of the bulb 131 with the result that communication is established between the interior of the bulb 131 and the bore 62 of the housing 63 of the pressurizing assembly 51 independently of any check valves and of the pressure control box assembly 52 which, as will be described in detail hereinbelow, is in communication with the main supply tube 54. As the result of this direct and uninterrupted connection between the interior of the bulb 131 and the bore 62 of the housing 63 the bulb 131 is delicately sensitive and substantially immediately responsive to changes of pressure created within the housing 63 in response to operation of the auxiliary bellows 56. Consequently, almost immediately upon the commencement of the pressure stroke of the bellows 56, the pressure created within the housing 63 is transmitted by the auxiliary tube 113 to the interior of the bulb 131

which is thereby expanded into closing relation with a valve seat 141 encircling the outer end of the exhalation port 127. On the other hand, almost immediately upon commencement of the suction or intake stroke of the bellows 56 the bulb 131 is caused to retract, opening the port 127 and thereby establishing direct communication between the bore 123 of the housing 121 and the atmosphere. Sensitivity and immediacy of response of the bulb 131 to changes of pressure thereinside are enhanced by forming the bulb 131 to resemble a substantially wafer-like design, as clearly illustrated in Figure 9, so that that surface 142 thereof proximal to the valve seal 141 is subject to being flexed outwardly in response to internal pressure much more readily than can a spherical or substantially spherical bulb be expanded.

One of the important details of the present invention is that it discharges the exhaled gases from the system at a point immediately adjacent the patient so that those exhaled gases contaminate the fresh supply of oxygen available to the patient for his next successive inhalation only throughout a minimum length of the supply tube. It is for this reason that the exhalation port 127 is arranged within the housing 121 which constitutes the outer end of the supply tube 54, i. e., the end thereof which is closest to the patient. This leaves only a minimum length of conduit interposed between the patient and that portion of the system at which actual discharge of exhaled gases to the atmosphere occurs. This length of conduit apt to contain contaminated, exhaled gases at the end of the exhalation period comprises the irreducible minimum of the conventional flexible interconnecting tube 146 carrying at its outer end an adaptor 147 conventionally employed as the means for connecting a breathing tube optionally to a breathing mask 116 or to a tracheotomy tube 117. Means are provided for releasably mounting the housing 121 in suitable location conveniently adjacent the head 12 of the patient occupying the shell 11 of the respirator. An extension 151 of the housing 121 carries a flange 152 at its outer end. This flange and a setscrew 153 threaded therethrough are adapted to be engaged in selected position of adjustment upon a rod 154 the upper end 156 of which is of an acute form to facilitate its being hooked over any conveniently located protruding portion of the respirator, such as one of the clamping screws 157 whereby the respirator's collar 42 is clamped in sealing position to the end 13 of the respirator's shell 11.

The pressure control box assembly 52 comprises a casing 161 which is hollow to provide a chamber 162 thereinside. A laterally extending flange 163 of the casing 161 is equipped with a clamp 164 at its outer end adapted to be engaged upon one of the legs 23 of the respirator, as illustrated in Figure 6, and securely, though removably attached thereto, as by a suitable manually operable setscrew 166. The flange 163 of the casing 161 also provides a convenient means for mounting a pressure gauge 167 which is operably connected to the chamber 162 by means of a suitable tube 168 so that the pressure sensitive element (not shown) of the gauge 167 is responsive to the pressure existing within the chamber 162.

Means are provided for equilibrating the pressure within the supply tube 54 and the chamber 162. A port 169 in a wall of the casing 161 leads from the chamber 162 through a collar 171 to

which one of the legs 172 of a tubular Y-joint, the other two legs 173 and 174 being interposed into the supply tube 54 with the result that communication is established between the bore of the tube 54 and the chamber 162. It might be mentioned here that the leg 172 of the Y-joint 175 fits tightly into the collar 171 to remain securely engaged therewith against accidental or inadvertent removal and yet can be removed therefrom when necessity for such removal arises by simply exerting sufficient manual force, drawing the Y-joint 175 away from the casing 161. This would permit a nurse or other attendant to remove the pressure control box from the pressure breathing system immediately should any emergency requiring such removal arise. The nurse then can place her hand partially over the exposed end of the leg 172 to regulate escape of oxygen from the Y-joint 175 and thus assure delivery of oxygen to the patient without being subject to the control of the pressure control valve which is operably associated with the control box assembly 52.

This pressure control valve is in the nature of a relief valve which automatically opens whenever the pressure within the system reaches a maximum which previously has been determined as being the pressure at which it is advisable to administer oxygen to the patient. It comprises a valve 181 carried at the outer end of a pivotally mounted arm 182 in position to engage a valve seat 183 encircling the outer end of a port 184 in one of the walls of the casing 161. The inner end of this port 184 opens into the chamber 162, hence this valve 181 is in the nature of a "flap valve" adapted to be opened, establishing communication between the chamber 162 and the atmosphere, whenever pressure within the chamber 162 exceeds a certain value as predetermined by the setting of a spring 186 encircling the pin 187 whereby the inner end of the arm 182 is pivotally mounted upon the casing 161. This pin 187 is rotatably mounted in an extension 188 of the casing 161 and carries on its exposed outer end a suitable lever 189 which facilitates turning the pin 187 and thereby varying the tension of the spring 186. Consequently, the relief valve 181 is regulable to open at whatever pressure within the pressure breathing apparatus is deemed to be the maximum safe pressure at which the gases can be supplied to the patient.

Preferably, the auxiliary pressure tube 113 is disposed throughout the major portion of its length inside the main supply tube 54 so as to avoid for an operator or attendant the inconvenience of having to handle two separate tubes when mounting or dismounting the device and when tending a patient within the iron lung. However, as mentioned hereinabove, an important detail of the present invention is that the pressure created within the exhalation valve control bulb 131 should coincide quite closely at any given time during the cycle of the machine's operation with the pressure then existing within the bore 62 of the housing 63 at the opposite end of the tube, and for this reason the auxiliary pressure tube 113 should by-pass the pressure control box assembly 52. With this object in view, two ends 196 of the auxiliary pressure tube 113 extend through the walls of the supply tube 54 closely adjacent the Y-joint 173 and these ends are interconnected by an elbow or U-shaped tube 197 attached to the Y-joint on its outer surface. Similarly, attachment of the supply tube 54 to the housing 121 of the head assembly 53 is facilitated by having the end 198 of the aux-

illary tube nearest the housing 121 pass out through the wall of the supply tube 154 closely adjacent its point of attachment to the housing 121 so that it, the auxiliary tube 113, can readily be connected to the bulb-mounting nipple 129 exteriorly of the supply tube 54.

In the same manner, the opposite end 199 of the auxiliary pressure tube 113 extends through the wall of the supply tube closely adjacent the connection of the latter to the housing 63 of the gas pressurized assembly 51, thus enabling the end 199 of the auxiliary pressure tube 113 to be connected to the housing 63 by a nipple 201 communicating with the by-pass 114 exteriorly of the supply tube 54 and of the coupling 112.

Operation

Since the requirements of different patients afflicted with poliomyelitis vary so widely and are fraught with so many intricacies beyond the realm of ordinary engineering, that they are fully understood only by medical specialists specifically trained for the purpose, the operation of the apparatus of the present invention will be discussed here only from the standpoint of its mechanical functions, leaving the medical and surgical aspects of the different types of treatments which can be benefited by the use of the method and apparatus to the members of the medical profession.

Suffice it therefore for the purposes of the present disclosure to explain only the mechanical functioning of the apparatus. Since the coupling of the auxiliary bellows 51 to the operating mechanism of the respirator's principal bellows 16 is such that the one is expanded while the other is contracted, the auxiliary bellows 56 will create pressure within its associated system during each phase of the cycle when the main bellows 16 is creating negative pressure within the shell 11. Consequently, each time negative pressure is created within the shell 11, causing expansion of the patient's thoracic cage, oxygen or other suitable gas or mixture of gases is supplied to the patient at positive pressure either through a facial mask 116 or tracheotomy tube 117. The spring 186 of the pressure control box assembly 52 should be so regulated that the auxiliary bellows 59 will develop and maintain for the balance of its compression stroke, pressure of oxygen adequate not only to overcome the resistance of the patient's upper respiratory system, but also to thoroughly ventilate the patient's lungs. It is readily apparent, however, how it is that application of gases to be breathed at positive pressure, to the patient's respiratory system, i. e., internally of the patient, makes it possible to operate the main bellows 16 in such a manner as to produce a partial vacuum within the shell 11 of considerably less magnitude than when the gases to be breathed by the patient are supplied only at atmospheric pressure.

Since both the main bellows 16 of the respirator and the auxiliary bellows 56 of my attachment therefor are operated by the same actuating mechanism, their positive synchronization of each other is assured so that when the main bellows 16 is creating a negative pressure the auxiliary bellows 56 is creating a positive pressure, and vice versa. Upon termination of the negative pressure stroke of the main bellows 16 and commencement of its positive pressure stroke, the auxiliary bellows 56 will commence its negative pressure stroke. The lowered pressure thus created within the casing 63 of the pressurizing assembly 51 will substantially in-

11

stantaneously be transmitted to the interior of the exhalation valve 131, causing the valve to open the port 127 and permitting the patient to exhale easily and naturally to the atmosphere through only a minimum length of conduit. As explained hereinabove, this will leave fresh uncontaminated gases so closely adjacent the patient that only an immaterial quantity of exhaled gases will have to be taken into his respiratory system before the fresh, pure gases reach him at the beginning of his next inhalation phase.

During the phase of the cycle when the auxiliary bellows 56 is expanding it will first draw all of the oxygen which has been stored within the accumulator bag 98 and thereafter throughout the remainder of its intake phase the bellows 56 will draw fresh air into the system throughout the filter pack 93. Upon termination of this phase, the bellows 56 will start to contract, raising the pressure within the system, closing the check valve 99, and forcing the gas through the opened check valve 113 through the supply tube and to the patient, all this occurring while the main bellows 16 is expanding and creating negative pressure within the shell 11 externally of the patient. Also while this is occurring the positive pressure which exists within the housing 63 of the pressurizing assembly 51 is transmitted through the auxiliary pressure tube 113 to the bulb valve 131, thus closing the port 127 and thereby assuring that the gases will be supplied to the patient internally at positive pressure. However, immediately upon commencement of the intake phase of the bellows 56 negative pressure will be created within the housing 63 and this, being transmitted through the auxiliary tube 113 to the bulb 131, will open the exhalation port 127, permitting the patient to exhale substantially directly to the atmosphere as hereinabove explained.

The pressure control assembly 52 maintains the pressure for which the apparatus has been set by regulation of the spring 186, throughout the inspiratory phase but any excess volume of air or oxygen is blown off through the relief valve 181.

Consequently, air or other gases are never forced into the patient's lungs beyond that expansion which the pressure for which the spring 186 and the negative pressure then existing within the shell 11, operating jointly with each other, will produce. As a precautionary measure, the valve 96 should be so adjusted as should also the length of stroke of the bellows 56 that a small quantity of the gases being administered will spill out through the relief valve 181 during each cycle, i. e., the stroke volume should be adjusted slightly to exceed the patient's requirements.

Under some conditions, it is desirable or necessary to install the respirator accessory without stopping the action of the respirator. This can be accomplished readily if certain precautions are taken. By compressing the auxiliary bellows 56 the bellows' actuating bracket 72 can be slipped into place upon and fastened to the respirator lever 21 and then the main base bracket 64 can be attached on the bar 69 of the respirator frame. The bracket 74 should then be adjusted along the lever 21 so as to assure the proper stroke for the bellows 56 as hereinabove explained. As long as the stroke volume is sufficient to produce some overflow out through the relief valve 181 of the control box assembly 52 at the end of each inspiratory phase of the cycle, the bellows' stroke is adequate.

12

When it proves to be desirable to open the shell 11 of the respirator for nursing or other care, the positive pressure being administered by the respirator attachment should be increased by proper manipulation of the lever 189 associated with the spring 186. This is one of the more important features of the present invention because it greatly facilitates performing those services for the benefit of the patient which require temporary discontinuance of the operation of the respirator proper.

I claim:

1. In combination, a respirator comprising a shell adapted to receive the chest of a patient and means for alternately lowering and then raising the pressure within said shell according to a predetermined cycle; and pressure breathing apparatus comprising a source of gas to be breathed, a supply tube leading therefrom, means for connecting said tube to the patient's respiratory system, a pump for intermittently raising the pressure of said gas within said tube, and means for connecting said pump to said respirator's pressure-varying means to be operated thereby and synchronously therewith, said connecting means being adjustable to attain variation of the stroke of said pump and of the volumetric output thereof.

2. An accessory for a respirator comprising a shell adapted to receive the chest of a patient and means for alternately creating negative and then positive pressure within said shell according to a predetermined cycle, said accessory comprising a bellows comprising a stationary member and a member movable with respect thereto for alternately drawing gas into said bellows and expelling said gas therefrom, means for mounting said bellows' stationary member on said respirator, means for operably connecting said bellows' movable member to said respirator's pressure-creating means to be operated thereby, means for connecting said bellows to a source of gas to be administered to said patient, a supply tube leading from said bellows, and means for connecting said supply tube to said patient's respiratory system.

3. An accessory for a respirator comprising a shell adapted to receive the chest of a patient and means for alternately creating negative and then positive pressure within said shell according to a predetermined cycle, said accessory comprising a bellows comprising a stationary member and a member movable with respect thereto for alternately drawing gas into said bellows and expelling said gas therefrom, means for mounting said bellows' stationary member on said respirator, means for operably connecting said bellows' movable member to said respirator's pressure-creating means to be operated thereby, means for connecting said bellows to a source of gas to be administered to said patient, a supply tube leading from said bellows, means for connecting said supply tube to said patient's respiratory system, means providing a pressure-relief port establishing communication between the interior of said supply tube and the atmosphere, a valve seat encircling the outer end of said port, a flap valve operably associated with said seat, and a spring yieldably pressing said valve against said seat to resist escape of gas from said tube through said port.

4. An accessory for a respirator comprising a shell adapted to receive the chest of a patient and means for alternately creating negative and positive pressure within said shell accord-

75

ing to a predetermined cycle, said accessory comprising a bellows comprising a stationary member and a member movable with respect thereto for alternately drawing gas into said bellows and expelling said gas therefrom, means for mounting said bellows' stationary member on said respirator, means for operably connecting said bellows' movable member to said respirator's pressure-creating means to be operated thereby, means for connecting said bellows to a source of gas to be administered to said patient, a supply tube leading from said bellows, means for connecting said supply tube to said patient's respiratory system, means providing a pressure-relief port establishing communication between the interior of said supply tube and the atmosphere, a valve seat encircling the outer end of said port, a flap valve operably associated with said seat, a spring yieldably pressing said valve against said seat to resist escape of gas from said tube through said port, and means for adjusting said spring to vary the pressure of gas within said tube necessary to unseat said valve.

5. An accessory for a respirator comprising a shell adapted to receive the chest of a patient and means for alternately creating negative and then positive pressure within said shell according to a predetermined cycle, said accessory comprising a bellows comprising a stationary member and a member movable with respect thereto for alternately drawing gas into said bellows and expelling said gas therefrom, means for mounting said bellows' stationary member on said respirator, means for operably connecting said bellows' movable member to said respirator's pressure-creating means to be operated thereby, means for connecting said bellows to a source of gas to be administered to said patient, a supply tube leading from said bellows, means for connecting said supply tube to said patient's respiratory system, pressure control means comprising a hollow box, means for connecting said tube thereto to establish communication between the interior of said box and the interior of said tube to equilibrate pressures therein, a port leading through a wall of said box, a valve port, an arm pivoted at one end for movement about an axis offset from said valve seat, a valve carried by the other end of said arm in position to engage said seat, a spring associated with said arm and yieldably pressing said valve onto said seat to resist escape of gas from said box through said port, and means for adjusting said spring to predetermine the pressure of gas within said box at which said valve will be unseated.

6. An accessory for a respirator comprising a shell adapted to receive the chest of a patient and means for alternately creating negative and then positive pressure within said shell according to a predetermined cycle, said accessory comprising a bellows comprising a stationary member and a member movable with respect thereto for alternately drawing gas into said bellows and expelling said gas therefrom, means for mounting said bellows' stationary member on said respirator, means for operably connecting said bellows' movable member to said respirator's pressure-creating means to be operated thereby, means for connecting said bellows to a source of gas to be administered to said patient, a supply tube leading from said bellows, means for connecting said supply tube to said patient's respiratory system, said supply tube having a port in the wall thereof opening to the atmosphere from said tube's interior and disposed closely adjacent the outer end of said tube, a

valve operatively associated with said port, and means operative in response to fluctuation of pressure within said tube for operating said valve.

5. An accessory for a respirator comprising a shell adapted to receive the chest of a patient and means for alternately creating negative and then positive pressure within said shell according to a predetermined cycle, said accessory comprising a bellows comprising a stationary member and a member movable with respect thereto for alternately drawing gas into said bellows and expelling said gas therefrom, means for mounting said bellows' stationary member on said respirator, means for operably connecting said bellows' movable member to said respirator's pressure-creating means to be operated thereby, means for connecting said bellows to a source of gas to be administered to said patient, a supply tube leading from said bellows, means for connecting said supply tube to said patient's respiratory system, said supply tube having a port in the wall thereof opening to the atmosphere from said tube's interior and disposed closely adjacent the outer end of said tube, a valve operatively associated with said port, and means operative in response to fluctuation of pressure within said tube for holding said valve closed during the gas-expelling phase of said bellows' operating cycle and for holding said valve open during the intake phase of said cycle.

8. An accessory for a respirator comprising a shell adapted to receive the chest of a patient and means for alternately creating negative and then positive pressure within said shell according to a predetermined cycle, said accessory comprising a bellows comprising a stationary member and a member movable with respect thereto for alternately drawing gas into said bellows and expelling said gas therefrom, means for mounting said bellows' stationary member on said respirator, means for operably connecting said bellows' movable member to said respirator's pressure-creating means to be operated thereby, means for connecting said bellows to a source of gas to be administered to said patient, a supply tube leading from said bellows, means for connecting said supply tube to said patient's respiratory system, said supply tube having a port in the wall thereof opening to the atmosphere from said tube's interior and disposed closely adjacent the outer end of said tube, a valve operatively associated with said port, and means operative in response to fluctuation of pressure within the portion of said tube adjacent said bellows for holding said valve closed during the gas-expelling phase of said bellows' operating cycle and for holding said valve open during the intake phase of said cycle.

9. An accessory for a respirator comprising a shell adapted to receive the chest of a patient and means for alternately creating negative and then positive pressure within said shell according to a predetermined cycle, said accessory comprising a bellows comprising a stationary member and a member movable with respect thereto for alternately drawing gas into said bellows and expelling said gas therefrom, means for mounting said bellows' stationary member on said respirator, means for operably connecting said bellows' movable member to said respirator's pressure-creating means to be operated thereby, means for connecting said bellows to a source of gas to be administered to said patient, a supply tube leading from said bellows, means for connecting said

supply tube to said patient's respiratory system comprising a tubular casing connected at one end to said supply tube and adapted at its other end for connection to the patient, said casing having a port therein opening from said casing's bore to the atmosphere, a valve seat encircling the outer end of said port, an arm rigid with said casing and extending adjacent said port, a hollow bulb of flexible material carried by said arm in position normally spaced outwardly from said seat, and an auxiliary tube establishing communication between the interior of said bellows and the interior of said bulb whereby gas is forced into said bulb and said bulb is expanded into closing relation with said seat at the beginning of the gas expelling phase of said bellows' cycle of operation and whereby gas is withdrawn from said bulb and said bulb is collapsed into port-opening relation at the beginning of the intake phase of said cycle.

10. An accessory for a respirator comprising a shell adapted to receive the chest of a patient and means for alternately creating negative and then positive pressure within said shell according to a predetermined cycle, said accessory comprising a bellows comprising a stationary member and a member movable with respect thereto for alternately drawing gas into said bellows and expelling said gas therefrom, means for mounting said bellows' stationary member on said respirator, means for operably connecting said bellows' movable member to said respirator's pressure-creating means to be operated thereby, means for connecting said bellows to a source of gas to be administered to said patient, a supply tube leading from said bellows, means for connecting said supply tube to said patient's respiratory system, means providing a pressure-relief port establishing communication between the interior of said supply tube and the atmosphere, a valve 15 seat encircling the outer end of said port, a flap valve operably associated with said seat, a spring yieldably pressing said valve against said seat to resist escape of gas from said tube through said port, means for adjusting said spring to vary the pressure of gas within said tube necessary to unseat said valve, said supply tube having an exhalation port in a wall thereof opening to the atmosphere from said tube's interior and disposed closely adjacent the point of connection 20 of said tube to said patient's respiratory system, an exhalation valve operatively associated with said exhalation port, and means operative in response to fluctuations of pressure within said tube adjacent said bellows for holding said exhalation valve closed during the gas-expelling phase of said bellows' operating cycle and for holding said exhalation valve open during the intake phase of said cycle.

11. An accessory for a respirator comprising a

shell adapted to receive the chest of a patient and means for alternately creating negative and then positive pressure within said shell according to a predetermined cycle, said accessory comprising a bellows comprising a stationary member and a member movable with respect thereto for alternately drawing gas into said bellows and expelling said gas therefrom, means for mounting said bellows' stationary member on said respirator, means for operably connecting said bellows' movable member to said respirator's pressure-creating means to be operated thereby, means for connecting said bellows to a source of gas to be administered to said patient, a supply tube leading from said bellows, means for connecting said supply tube to said patient's respiratory system, means providing a pressure-relief port establishing communication between the interior of said supply tube and the atmosphere, a valve seat encircling the outer end of said port, a flap valve operably associated with said seat, a spring yieldably pressing said valve against said seat to resist escape of gas from said tube through said port, means for adjusting said spring to vary the pressure of gas within said tube necessary to unseat said valve, said means for connecting said supply tube to the patient's respiratory system comprising a tubular casing connected at one end to said supply tube and adapted at its other end for connection to the patient, said casing having an inhalation port therein opening from said casing's bore to the atmosphere, a valve seat encircling the outer end of said inhalation port, an arm rigid with said casing and extending adjacent said inhalation port, a hollow bulb of flexible material carried by said arm in position normally spaced outwardly from said seat, and an auxiliary tube establishing communication between the interior of said bellows and the interior of said bulb whereby gas is forced into said bulb and said bulb is expanded into closing relation with said seat at the beginning of the gas expelling phase of said bellows' cycle of operation and whereby gas is withdrawn from said bulb and said bulb is collapsed into port-opening relation at the beginning of the intake phase of said cycle.
